(57) **CLAIM**

The ornamental design for an air vent for a vehicle, as shown and described.

DESCRIPTION

This application is related to the following co-pending applications, of the inventor, filed on even date herewith: application Ser. No. 29/217,787, entitled “Surface Configuration of a Vehicle, Toy and/or Other Replicas”; and application Ser. No. 29/217,767, entitled “Surface Configuration of a Vehicle, Toy and/or Other Replicas”.

FIG. 1 is a front view of a first embodiment of an air vent for a vehicle according to my novel design;

FIG. 2 is a front perspective view thereof; and,

FIG. 3 is a rear perspective view thereof.

FIG. 4 is a front view of a second embodiment of the air vent for a vehicle according to my novel design;

FIG. 5 is a front perspective view thereof; and,

FIG. 6 is a rear perspective view thereof.

The broken lines are for illustrative purposes only and form no part of the claimed design.

1 Claim, 4 Drawing Sheets

FIG. 2

FIG. 1

FIG. 3

FIG. 4

FIG. 5

FIG. 6
